UNITED STATES PATENT OFFICE.

GEORGE H. TOWNSEND, OF MADISON, WISCONSIN.

EQUALIZING DEVICE.

1,314,719.

Specification of Letters Patent.

Patented Sept. 2, 1919.

Application filed January 5, 1917. Serial No. 140,658.

To all whom it may concern:

Be it known that I, GEORGE H. TOWNSEND, a citizen of the United States, residing at Madison, in the county of Dane and State 5 of Wisconsin, have invented certain new and useful Improvements in Equalizing Devices, of which the following is a specification.

My invention relates to equalizing devices 10 applicable to ladders and movable platform supports requiring adjustment to uneven surfaces. The object of my invention is to provide means to practically shorten or lengthen the legs or support of the appliances to meet 15 any unevenness or incline of the surface where such appliances are used. I attain these results by a construction illustrated in the accompanying drawing in which—

Figure 1 is a rear elevation as applied to a 20 ladder.

Fig. 2 is a side elevation of same.

Fig. 3 is an enlarged fragmental elevation of Fig. 1 showing the compound swivel, mounted with legs attached.

Fig. 4 is a plan of link, mounted, carrying 25 compound swivel clips and legs mounted.

Fig. 5 is an elevation of a swivel link designed as a leg holder.

Fig. 6 is a plan of swivel link leg holder 30 shown in Fig. 5.

The same numbers refer to similar parts in the several views and descriptions in the singular apply to a plurality of similar parts.

35 My invention consists of a rectangular link 7 adapted to slide back and forth and also to oscillate when mounted on transverse pivot rod 8 and also adapted for mounting compound clips 9 on pivot 10 and arranged

40 to oscillate so that the clips 9 do not change their angle in relation to the sides of the ladder 11 with the oscillation of link 7 on pivot rod 8. The compound swivel clips 9 are constructed to engage legs 12 mounted on

45 and held in position by pivots 13 so as to permit legs 12 to change their angle as link 7 with compound clips 9 slides back and forth on pivot rod 8 thereby raising or lowering legs 12 to adjust them to uneven surfaces.

To the under or back edge near the base of 50 ladder sides 11 a transverse bar 14 is attached for the mounting of swivel link leg holder 15 oscillating on pivot 16 as the angle of leg 12 is varied by sliding back and forth of link 7 on pivot rod 8. In operating, lifting the ladder allows the adjustable legs 12 to drop enough to loosen the swivel link leg holders 15 from legs 12 which may be placed where desired and the ladder shifted to proper angle, automatically adjusting it to 55 even or uneven surfaces and locking the device by the weight of the ladder by sliding link leg holders 15 on legs 12.

What I claim as my invention for which I desire Letters Patent is—

1. In an equalizing device for ladders, adjustable brace legs pivotally attached to swivel clips on either side of a band link mounted on a pivot rod and adapted to oscillate and slide back and forth between the 60 sides of the ladder to which the device is attached substantially as set forth.

2. In an equalizer for ladders, swivel leg holders mounted on a cross bar attached to a ladder, through which adjustable legs loosely 65 pass, the ends of which are pivotally attached to swivel clips on either side of a band link mounted on a pivot rod and adapted to oscillate and slide back and forth between the sides of the ladder to which the 70 device is attached, substantially as set forth.

3. In an equalizer adapted to ladders, swivel leg holders, through which adjustable legs loosely pass, the ends of which are pivotally attached to swivel clips on 75 either side of a band link, pivotally mounted on a rod and adapted to oscillate and slide back and forth between the sides of the ladder to which the device is attached, to release the adjustable legs in the swivel leg 80 holders when the ladder is lifted and clamp them when the ladder is set for use.

In testimony whereof I affix my signature in the presence of two subscribing witnesses.

GEORGE H. TOWNSEND.
